UNITED STATES PATENT OFFICE

FRANK C. MOCK, OF CHICAGO, ILLINOIS, ASSIGNOR TO BENDIX STROMBERG CARBURETOR COMPANY, OF CHICAGO, ILLINOIS, A CORPORATION OF ILLINOIS

AIRPLANE CARBURETOR

Original application filed January 16, 1924, Serial No. 686,474. Divided and this application filed March 18, 1926, Serial No. 95,517. Renewed April 11, 1929.

My invention relates to carburetors, but more especially to airplane carburetors, and is a division of my co-pending application, Serial No. 686,474, filed January 16, 1924, 5 which has matured into Patent No. 1,600,008 of Sept. 14, 1926.

The invention covers particularly improved idling and economizing arrangement and operation.

10 On the drawings which illustrate the various features of my invention:—

Figure 1 is a plan view of a double barrel carburetor;

Fig. 2 is a transverse sectional view on line 15 2—2 of Fig. 1;

Fig. 3 is a horizontal sectional view on line 3—3 of Fig. 2;

Fig. 4 is a transverse sectional view taken approximately on line 4—4 of Fig. 1;

20 Fig. 5 is a transverse fragmentary sectional view taken approximately on line 5—5 of Fig. 1;

Fig. 6 is a fragmentary sectional view through the idling tube taken approximately 25 on line 6—6 of Fig. 5;

Fig. 7 is a fragmentary sectional view taken approximately on line 7—7 of Fig. 3;

Fig. 8 is a detail elevational view illustrating the adjusting arm for the idling plug;

30 Fig. 9 is an elevational view of the idling plug as viewed from within the carburetor barrel.

The structure shown on the drawings comprises a casing 22 constructed of a lower casting section 23 and an upper casting section 24 joining along the split line 25, a gasket 26 being preferably interposed between the casting sections. It will be noted that this split 35 line is above the normal fuel level. Extending

40 up through the lower casting section 23 are the two carburetor barrels 27—27, these barrels being extended up through the upper casting section 24. Mounted in each barrel is a Venturi tube 28, and discharging adjacent the throat of this venturi is a main nozzle 29. A throttle valve 31 mounted on a transverse throttle shaft 32, controls the flow through each barrel. The arrangement 45 of Venturi tube, nozzle, and throttle in one

barrel is practically a counterpart of the arrangement in the other.

A float chamber, designated 33 in its entirety, substantially surrounds the two carburetor barrels 27 on the front, back and one 55 side of the barrels. The front and rear areas 34 and 35 of this float chamber are of substantially the same capacity, and are cross connected on the longitudinal axis of the carburetor by a tube 36 (Fig. 2) which quickly 60 conducts the fuel from one chamber area to the other when the carburetor is being inclined on this longitudinal axis. Two substantially drum shaped floats 37 of equal size are supported in the chamber areas 34 65 and 35 on the arms 38 of a yoke 39. It will be noted that these floats are supported with their axes substantially coincident with the median plane of the carburetor between the two barrels 27.

The lateral portion 41 of the float chamber extending around the outer side of one of the barrels, receives the float controlled valve 42 which maintains a predetermined level of fuel in the chamber 33. The upper end of the 70 valve 42 is slotted laterally for hooking over a pin 43, which pin is carried in a bifurcated or notched portion of the yoke 39, as shown in Figure 3. Yoke 39 is pivotally supported upon pivot pins 44, having threaded shanks, 75 screwing into the carburetor body at opposite points. As shown in Fig. 7, the valve 42 is guided in a tubular plug 45 having a valve seat in its lower end. This valve seat is faced by a hardened metal bushing 46 for 80 engagement with the valve 42, the tubular plug 45 being of aluminum or some other light weight metal.

Fuel is supplied to valve seat bushing 46 through a cored passageway 47, which extends diagonally across the rear part of the carburetor casting to a fuel strainer 48, as shown in Fig. 3. As shown in Fig. 2, the strainer is built up of upper and lower sheet metal caps 49 and 51 connected by a plurality 85 of longitudinal spacing rods 52. A cylindrical screen 53 of fine mesh encircles the cylindrical frame defined by the rods 52 between the end caps 49 and 51. The strainer 90 is supported in a straining chamber 54, cast 95 in the carburetor casting. The strainer 54 is supported in a straining chamber 54, cast 100

integral with the lower casing section 23. A threaded cap 55 closes the open top of this straining chamber and compresses a spring 56 down against the top of the straining screen. The fuel is admitted from the supply tank into the straining chamber 54 through a lateral port 57, shown in plan in Fig. 1. A tube 58 passes down through the screen 48, eccentrically thereof as shown in Fig. 3, and the lower end of this tube is anchored in a tubular boss 59 at the bottom of the straining chamber. The supply passageway 47 opens laterally through the wall of the boss 59 and of the tube 58 for receiving the strained fuel fed down through the upper end of the tube 58. The spring 56 quiets all tendency of the strainer to vibrate or rattle, and by the simple removal of the plug 55 the strainer is instantly accessible for cleaning. Its location at the rear of the carburetor aids in retaining the carburetor of relatively narrow transverse dimension for setting down within the V of aeronautic engines.

It will be observed that I have proportioned the parts so that the normal fuel level indicated on Fig. 2 by the dash and dot line X—X will lie slightly higher than the centers of the floats 37—37. This places a relatively large quantity of fuel in the float chamber, so that at relatively large angles of either fore or aft inclination there will be ample fuel to buoy up the float mechanism and to maintain the fuel supply ports 61 leading to the fuel nozzles covered with fuel. It will also be noted that as the fuel shifts from one float chamber area to the other through passage 36, with the fore and aft inclination of the craft, the lesser buoyancy of the float on the high end will be compensated for by the increased buoyancy of the float on the low end, because of the greater submergence of this low float. As before stated, the centers of buoyancy of the floats are in a median plane between the two carburetor barrels, and the chamber areas 34 and 35 are so proportioned on each side of the common axis of these floats that in lateral inclination of the carburetor the fuel level will tend to revolve substantially around the common center of buoyancy of the float. As the result of this there is minimum possibility of either fuel nozzle being starved of fuel during lateral inclination of the air craft.

I can proportion the two floats and their related parts so that the fuel level during fore and aft inclination of the craft will remain at the same normal height relative to the tip of the nozzle as during horizontal flying; but I prefer to actually proportion these parts so that there will be an appreciable rise of level relative to the nozzle when the craft is inclined either forwardly or backwardly. In a typical embodiment I design the parts so that the fuel valve will have a closing pres-

sure of approximately fourteen-twelfths times the buoyancy of one float completely submerged. Consequently, when in the backward or forward inclination of the craft, the fuel rushes to the front or back, submerging one float, this totally submerged float will be incapable alone of holding the fuel valve on its seat. If two-twelfths of the buoyancy of the other float is not supported by fuel in the other part of the float chamber, the fuel valve will open and fuel will enter until this two-twelfths of the float buoyancy is made up. This will raise the level relative to the nozzle outlet. Any proportion of floats and valves may be utilized to raise the fuel level a greater or lesser height.

The floats are internally braced by tubular bracing struts 60 extending across the same centrally. Without such braces these floats have collapsed in service, due probably to back-fire pressures.

Fuel is supplied to the two nozzles 29 through individual ducts 61 which open into the bottom of the float chamber at points close to the longitudinal median plane of the float chamber, as indicated in Fig. 3. Each duct then leads laterally out to a bore 62 which is extended horizontally to the lower end of the nozzle, as indicated in Fig. 5. The outer end of each bore 62 is closed by a removable plug 63 and a calibrated plug 64 is passed through this outer end and is screwed into a thread between the bore 62 and its reduced continuation 62'. The calibrated plug is provided with two similar counterbores 65 in its ends, and a short restricted passageway 66 between these bores. It will be noted that the restricting channel 66 is set in from each end of the plug, and from the screw driver kerf in the end of the plug, so that there is little possibility of damaging this restricting channel 66 by the screw driver in inserting the plug, or by any object striking the end of the plug. These plugs are carefully made and very carefully calibrated as to flow before they are placed in stock, and it is quite important that the same capacity of flow be thereafter preserved.

The duct 62' discharges into a relatively large bore 67 which is closed at the bottom by a screw plug 68 directly below each nozzle. A nozzle plug 69 is inserted through the upper reduced end of the bore 67, the threaded upper end of this plug screwing into a nut 71. The nozzle in its entirety is supported upon the bridge or pair of spider arms 72 extending across the air intake 73. The bore 62' extends through this bridge or spider construction, and the nut 71 screws down upon the top of this bridge member. The nut 71 is formed with a reduced sleeve 74 extending upwardly therefrom, and threaded at its upper end for receiving the outer nozzle sleeve 75. The lower part of the sleeve 75 is spaced outwardly from the sleeve 74 to form an inter-

vening accelerating well 76. This well has venting communication into the bore of the inner sleeve 74 through a plurality of radial apertures 77 adjacent the upper and lower ends of the well. As shown in Fig. 2, the outer nozzle sleeve 75 is formed with a laterally extending tubular arm 78, from the outer end of which extends an upright tube 79 to a point adjacent the top of the nozzle. A metering plug 81 closes the upper end of the channel 79 and controls the volume of venting air which is held down through the channel 79 and arm 78 into the accelerating well 76.

Referring again to the nozzle plug 69, it will be noted that the liquid fuel is conducted through a central passageway 82, around which are grouped a plurality of small air venting ducts 83. Both the fuel passageway 82 and the air ducts 83 open at the upper end of the plug 69 into the enlarged lower end of the sleeve 74, but at their lower ends the ducts 83 open laterally into an annular groove around the body of the plug which communicates with a horizontal air duct 85 extending out through the other arm of the bridge or spider 72. During such times as the idling jet, which I shall hereinafter describe, is in operation, the ducts 83 and 85 draw fuel from the sleeve 74 for supplying said idling jet. During the other extreme of operation, however, when the throttle is relatively wide open the suction effective at the nozzle 29 will be higher than that effective at the idling jet, with the result that a reverse circulation will be set up, drawing air down through the idling jet and idling passageway and through the ducts 85 and 83 for venting into the fuel stream flowing upwardly through the passageways 82 and 74. Attention is directed to the fact that the vertical ducts 83 convey this venting air up above the level of the duct 85 and to a relatively high point in the nozzle before mixing the air with a fuel stream. A particular advantage accrues through this arrangement. With an air bleed type of nozzle and a submerged fuel restriction, such as indicated at 64, the fuel flow is proportional to the square root of the suction across the restricting orifice, plus the gravity head from the float level to the point where the air bleed entering the emulsion passage begins to take the weight off of the fuel column. To obtain a uniform mixture it is frequently desirable to reduce this last factor of the gravity head from the float level to the point where the vented air enters the fuel stream. This is attained in the present construction by the ducts conveying this venting air up to the elevated point shown before mixing with the fuel flowing to the emulsion passageway. Obviously, these ducts 83 can be extended up to any desired elevation in the nozzle by extending

the plug 69 up to the desired point in the inner nozzle sleeve 74.

As above stated, the fuel flow is substantially proportional to the square root of the suction across the restricting orifice plus the gravity head from the float level to the point where the vented air enters the emulsion passage. The air flow is quite closely proportional to the square root of the suction; therefore, to maintain a uniform mixture the air bleed holes entering the emulsion passage should be quite close to the fuel level. This applies to the holes 77 from the accelerating well 76, as well as to the ducts 83. Pursuant thereto, the whole accelerating well 76 has been built up close to the fuel level, and in giving the well its desired capacity this has meant that the outer dimension of the discharge nozzle 29 is relatively large. If a large straight nozzle of this size is used in a venturi of the approximate size shown, there is a tendency for the fuel to draw into the eddy space above the nozzle in an accumulation of liquid and large drops. This I have counteracted by extending a flange 86 partly beyond the cylindrical portion of the well and immediately below the lateral outlet port 87 through which the fuel is discharged from the upper end of the nozzle. This flange 86 is sloped upwardly at a slight angle, and operates to deflect outwardly from the nozzle, the air current entering the venturi along the sides of the nozzle body. This outwardly deflected current of air tends to impel the fuel particles discharged laterally from the ports 87 outwardly from the sides of the nozzle into the main body of the air stream flowing between the nozzle and the venturi. This action can be augmented by sloping the top of the jet downwardly and outwardly as indicated at 88, whereby there is induced a downward and outward current of air off of the top of the nozzle which combines with the laterally discharging fuel and the laterally deflected current of air rising from the inclined shoulder 86.

A relatively narrow flange 86 will create the desired outward current of air for securing the above results; and if the flange is too wide this outward current of air will become so strong as to undesirably disturb or break up the Venturi action. In practice I have made these flanges 86 as narrow as one thirty-second of an inch and secured the desired result. In co-operation with this design of nozzle I have employed a two-taper Venturi tube 28, such as indicated in Fig. 5. This Venturi tube has a lower angle of approximately one and a half to two degrees on a side, this lower angle being designated γ and extending a short distance beyond the point where the fuel nozzle discharges into the air stream. The upper angle, designated α , is about 7 degrees on a side extending from

the termination of the lower angle out to approximately the discharge end of the Venturi tube. The slow taper γ limits the expanding action of the air stream at a point 5 where the disturbance, caused by the discharge of the fuel, is greatest, and then the large taper allows the Venturi action to take place to a greater degree after the fuel droplets have taken up travel substantially parallel to the air stream. The offset of the flange 86 does not seriously interfere with the Venturi action, as above stated, and does give the directive effect desired so long as the fuel spray is broken up by the venting 10 of air into the fuel stream passing up through the nozzle tube 74. When the fuel spray is not broken up, this relatively small offset is not sufficient to impel the larger drops outwardly. The step of venting air into the 15 fuel stream thus assists materially in the action of the flange 86 and the two-taper venturi 28.

The supply of fuel for the idling jet is conducted through duct 85 to a nozzle 89 having 20 a calibrated fuel passageway 91, and it will be noted that this passageway is submerged below the normal liquid level. An idling tube 92 is screwed into a vertical bore 93 extending through the upper and lower sections of the carburetor casing, and the lower end of this tube is slightly flared to receive the fuel discharged from the nozzle 89. The tube 92 is spaced from the bore 93 so that air may be vented down around the outside 25 of the tube 92 for bleeding into the fuel stream around the lower end of the tube 92 in immediate proximity to the nozzle. Air is admitted to the annular space around the tube 92 through a plug 94 which has lateral 30 air ports 94' communicating with this annular space, as indicated at Fig. 6. The plug 94 is offset laterally with respect to the idling tube and is inclined downwardly in alignment with the bore 95 which opens into an 35 annular recess or groove 96 around the outside of the Venturi 28. The plug 94 has a restricted orifice 97 for controlling the volume of this vented air, which volume can be readily varied by the simple substitution of 40 plugs 94 having larger or smaller orifices. The annular space 96 around the Venturi tube has communication through ports 98 (Fig. 4) with a lower annular space 99 which opens into the lower air intake of the carburetor 45 through the slot 101 in the central wall.

The upper end of the idling tube 92 communicates with the cored passageway 102 which extends around through the wall of the carburetor barrel to the outer side of its respective barrel. Here this passageway communicates with a transverse fuel channel 103 in the idling plug 104, substantially as illustrated in Figs. 4 and 9. This plug is formed with a reduced inner end to form a shoulder 50 for abutting a shoulder 105 in the boss 106

in which the plug is supported. A flanged bushing 107 screws into the outer end of this boss and supports a compression spring 108 which thrusts the plug up against the shoulder 105. The inner reduced end of the idling plug opens into the carburetor barrel 27, terminating substantially flush with the wall of the barrel substantially in coincidence with the lower edge of the throttle 31 when the throttle is in closed position. As shown in Fig. 9, this end of the plug is provided with an idling port 109 communicating with the channel 103 and disposed eccentrically of the plug. It will be evident that by rotating the plug 104 this eccentrically disposed idling port can be shifted to discharge above, below, or to partially intersect the lip of the throttle in any one of a plurality of positions. This permits of a wide graduation of the idling mixture proportions, as I shall presently describe. A reduced shank or stem 111 extends through the flanged bushing 107 and has pinned thereto an operating arm 112 which is adapted to take any one of a plurality of adjustable settings over a quadrant 113. This quadrant is secured by screws between the flange on the bushing 107 and the end of the boss 106. A spring detent 114 carried in the outer end of the arm 112 is adapted to engage in recesses 115 in the periphery of the quadrant 113. The provision of this outer operating arm 112 enables the idling jet to be quickly and easily adjusted during the operation of the motor.

The present construction of idling system and the co-operative relation between the two idling adjustments is of great importance in enlarging the size of the main venturi in overcoming the lean spot in the transition between idling operation and main jet operation. One of the aims of the present construction has been to provide a "two-stage" carburetor, i. e., one in which the so-called idling jet supplies the fuel over a part of the running range of the engine, which is relatively large as compared to previous idling jet practice. In the present instance this idling jet range runs from the lowest engine speed up to approximately 800 R. P. M., this being the "first stage", and the main jet range runs from this point on up to the highest engine speed, as the "second stage".

In airplane practice it is desirable to increase the size of the main venturi 28 to as large an extent as possible for maximum volumetric efficiency and for drawing in the greatest volume of air possible at high altitudes. The chief limitation on the size of the main venturi has been the lean spot in the transition from idling jet operation to main jet operation. Where the venturi size is increased this lean spot is increased, and there are numerous carburetors now made in which the main venturi is undesirably restricted in order to overcome this lean spot. I over-

come this lean spot and increase the permissible size of the main venturi by extending the idling range to a relatively high speed through the use of the present construction 5 of idling system, including the air bleed and rotatable plug adjustments.

The size of the air bleed restriction 97 in its relation to the size of the fuel metering orifice 91 is a fundamental adjustment by 10 which the mixture proportions for practically the entire idling range are obtainable. Moreover, this bleeding of a calibrated amount of air into the idling column of fuel 15 considerably below the fuel level reduces the weight of the column and greatly extends the range of delivery of a properly proportioned idling or "first stage" mixture. The ready removability of the plug 94 from the exterior of the carburetor without necessitating the removal of other plugs, screws, 20 etc., permits of the quick substitution of these plugs for increasing or decreasing the volume of air bled into the idling system and thereby varying this fundamental 25 adjustment.

I find it desirable to provide a finer adjustment for the low speed end of this idling or "first stage" range, and, accordingly, I superpose on this fundamental adjustment a 30 secondary adjustment in the form of the rotatable idling plug 104. As the throttle is closed down to 300 R. P. M., or the lower speeds of the motor, it is possible by rotation of the idling plug 104 to secure the exact 35 mixture proportion desired, regardless of inevitable variations in fit of the throttle valve, or other structural variations, or of the leakage of air into the intake system through other points. The very high manifold suction 40 existing during these low engine speeds results in a higher degree of air leakage into the manifold system through the valve guides, manifold connections, etc., than at any other speed.

45 As the throttle is opened up towards 800 R. P. M., or the upper end of the idling or "first stage" operation, the edge of the throttle is carried past the idling port 109 to such an extent that the precise location 50 of this idling port will exert very little control over the idling mixture. At this time the idling mixture is controlled by the selected restriction of the air metering orifice 97, relative to a predetermined size of fuel 55 metering orifice 91.

Owing to the fact that the present idling system is producing an adequate, properly proportioned volume of idling fuel at the relatively high engine speed of approximately 60 800 R. P. M., the considerable throttle opening corresponding to this engine speed will be transmitting an effective suction to the main venturi, so that the transition from idling jet operation to main jet operation 65 will be a blended one.

It will be evident from the foregoing that the two idling adjustments or controls cooperate to cover the entire range of idling speeds, and inasmuch as both are externally adjustable or selective, the task of testing or 70 adjusting the carburetor is greatly simplified.

It will be noted that the idling bore 93 and tube 92 contain an ample supply of fuel for priming, and the quick ejection of this fuel 75 up through the idling jet is assured by the provision of the air bleeding passageway 95 and plug 94. This priming supply is instantly available by closing the throttle and cranking the engine.

When the throttle is moved to open position and the main jet 29 comes into active operation, the fuel contained in the idling system is drawn back into the main nozzle and thereafter air is bled back through the idling 80 system into the main nozzle. This counterflow of air occurs when the suction effective at the main nozzle is higher than the suction effective in the groove 96 around the outside of the Venturi tube. This counter-flow of air 85 can therefore be made to occur at a selected speed by connecting the groove 96 to the air passageway at the proper point. In Fig. 4 the groove is shown as connected through ports 98 and space 99 to the pressure prevailing in the air entrance. By closing this 90 opening of the groove and substituting a port which opens into the Venturi tube, as indicated in dotted lines at 100, the suction in the groove can be raised. The particular 95 location of this port relative to the length of the venturi will also determine the suction in the groove and the approximate engine speed at which this counterflow of air 100 will begin.

Having described my invention, I claim as 105 follows:—

1. In a carburetor, the combination of a carbureting chamber, a throttle controlling the flow therethrough, a plug rotatably 110 mounted in the wall of said chamber adjacent said throttle, an idling orifice in said plug discharging into said chamber, means extending from said plug to the exterior of the carburetor, an operating member on said 115 extending means, and detent means for holding said plug in adjusted position.

2. In a carburetor, the combination of a carbureting chamber having a throttle valve therein, a plug rotatably mounted in the 120 wall of said carbureting chamber adjacent said throttle valve, an idling jet in said plug adapted to be displaced relative to said throttle by the rotation of said plug, a shank extending from said plug to the exterior of the 125 carburetor, an arm on the outer end of said shank, a quadrant over which said arm is adapted to rotate, and means for holding said arm in different adjusted positions relative to said quadrant.

3. In a carburetor the combination of a carbureting chamber having a throttle valve therein, a plug rotatably mounted in the wall of said carbureting chamber adjacent said throttle valve, an idling port in said plug adapted to be displaced relative to said throttle valve by the rotation of said plug, a shank extending from said plug to the exterior of the carburetor, a bushing for said shank secured to the wall of the carbureting chamber, a spring between said bushing and said plug for holding said plug in operating position, and an actuating lever secured to the outer end of said shank.
- 10 4. In a carburetor, the combination of a carbureting chamber having a throttle valve therein, a fuel plug discharging into said chamber adjacent said throttle valve, said fuel plug being rotatable for changing the location thereof relative to said throttle valve, a lever at the outer end of said plug, a quadrant secured to the carburetor frame adjacent said plug, said lever having frictional engagement with said quadrant to thereby yieldably lock said plug in adjusted position.
- 15 5. In a carburetor having a carbureting chamber, a throttle valve in said chamber a main nozzle in said chamber, an idling nozzle discharging into said chamber adjacent said throttle, a passageway supplying fuel to said nozzle, an air-venting duct from said chamber to said passageway said duct opening into said chamber anteriorly of said main nozzle, and means for adjusting the position of said nozzle relative to said throttle.
- 20 6. In a carburetor having a carbureting chamber, a throttle valve in said chamber a main nozzle in said chamber, an idling nozzle discharging into said chamber adjacent said throttle, a priming well, a fuel supply tube communicating with said nozzle and depending in said well below the normal fuel
- 25 level therein, an air-venting duct leading from a point in said chamber anteriorly of said main nozzle to said well and tube, and means for adjusting the position of said nozzle relative to said throttle.
- 30 50 In witness whereof, I hereunto subscribe my name this 9th day of March, 1926.

FRANK C. MOCK.

CERTIFICATE OF CORRECTION.

Patent No. 1,871,460.

August 16, 1932.

FRANK C. MOCK.

It is hereby certified that error appears in the printed specification of the above numbered patent requiring correction as follows: Page 3, line 12, for the word "held" read bled; and that the said Letters Patent should be read with this correction therein that the same may conform to the record of the case in the Patent Office.

Signed and sealed this 29th day of November, A. D. 1932.
